UNITED STATES PATENT OFFICE.

HUGH WHITE, OF CHICAGO, ILLINOIS, ASSIGNOR TO MORRISON GARST AND WILLIAM L. HEATON.

BOOT AND SHOE.

SPECIFICATION forming part of Letters Patent No. 239,285, dated March 22, 1881.

Application filed November 15, 1880. (No model.)

To all whom it may concern:

Be it known that I, HUGH WHITE, of Chicago, in the county of Cook and State of Illinois, have invented certain Improvements in Boots and Shoes, of which the following is a specification.

This invention relates to improvements in boots and shoes for wear in rolling-mills and similar places where heat is to be guarded against. In this class of foot-gear it has been customary to hobnail the soles to lift the leather above contact with the heated surfaces whereon the wearer stands or walks, and also, in some instances, perforated metal plates have been applied to the tread of the soles for the like purpose. This, of course, protects the leather in some degree; but both the nails and the plates become so heated after exposure for a short time that they transmit the heat to the leather, and the latter in time becomes as effectually ruined as it would have been had it been allowed to rest directly upon the floor or heated surfaces. Sometimes, also, the tread of the soles has been guarded by under-soles of wood; but such under-soles are stiff and also sensitive to the injurious action of heat.

My invention is designed to obviate the objections to these and similar kinds of soles; and it consists in constructing the shoe with an under covering of asbestos, secured in place and protected against abrasive wear by hobnails, substantially as hereinafter set forth.

In the accompanying drawings, forming a part of this specification, and wherein Figure 1 is a side view, Fig. 2 a bottom view, and Fig. 3 a section upon the line *x y* of Fig. 2, of my invention, like letters indicate like parts wherever used.

In said drawings, A represents the sole and heel, as ordinarily made, of a boot or shoe. Applied to the bottom thereof, and preferably covering the entire under surface or tread, is a layer, B, of asbestos, which, as is well known, is in some of its forms flexible, so as to per-

mit the sole to bend, and is also a material not 45 injuriously affected by heat and a non-conductor thereof. Asstated, this asbestos should preferably cover the entire under surface of the sole, but it may not be employed under the shank, nor under the heel. I recommend 50 its use, however, under the whole shoe, as thereby the entire sole is protected from the heat radiated from the floor.

In order that the asbestos may not receive wear, and to securely fasten it to the boot, I 55 stud the entire bottom, or so much thereof as is covered by the asbestos, with hobnails C and C', which pass through it into the leather of the sole. Of these hobnails those marked C' are placed around the edges, and are provided upon one side with an upwardly-projecting ear, *e*, which is made to hug the edges of the asbestos and leather, as indicated in the drawings, thereby protecting such edge from contact with exterior objects and preventing 60 injury to it. If the boot is to be worn in the wet, the asbestos is preferably coated with some water-proof material which is not readily inflammable and will retain its water-turning quality under the action of such heat as the 70 boot will be subjected to in ordinary use.

By my method of manufacture the heads of the nails do not come in contact with the leather, and the latter receives only a small fraction of the heat through their points and 75 the ears of those at the sides, which is a great advantage over the old construction.

I claim—

The boot or shoe, for use in rolling-mills or similar places, provided with an under covering of asbestos secured in place and protected from abrasive wear by hobnails, as shown and described.

HUGH WHITE.
